CONTAINER FOR CARDS

Forest H. Hartzell, Dayton, Ohio

Application May 5, 1933, Serial No. 669,490

12 Claims. (Cl. 206—40)

This invention relates to improvements in card containers, and has for its object to provide a small case adapted to contain a plurality of business or visiting cards, and to discharge these cards one at a time as desired.

It is the object of this invention to provide a card case having an outlet slot therein, means to support cards in the case in such a position that the cards may be delivered from the case one at a time through the slot, and means in the case for discharging the cards in this manner.

It is also an object of this invention to provide a card case, rectangular in shape, with one end open and the other provided with a slot, and a card carrier adapted to be inserted into the open end of the case for closing it, and having means thereon in the case for maintaining the cards in a position to be ejected through the slot in the closed end of the case.

It is a further object of this invention to provide a metallic card case having means on one side for ejecting cards one at a time, and the other side polished to form a mirror.

It is an object to provide a card case with a protective wrapping thereon, permanently attached thereto and forming an outer shell for the case.

These and other advantages will appear from the following description taken in connection with the drawings.

Referring to the drawings:

Figure 1 is a top plan view of one form of card case.

Figure 2 is an edge elevation of the case shown in Figure 1.

Figure 3 is an end elevation of the case shown in Figure 1.

Figure 4 is a top plan view of a slightly modified form of case.

Figure 5 is a view showing one lateral edge of the case shown in Figure 4.

Figure 6 is a view showing the bottom of the case shown in Figures 4 and 5, which bottom is polished to form a mirror.

Figure 7 is an end view of the case shown in Figure 4.

Figure 8 is a section on the line 8—8 of Figure 1.

Figure 9 is a section similar to that shown in Figure 8 but with the card discharging means in a position for ejecting one of the cards, showing one of the cards in ejected position.

Figure 10 is a section on the line 10—10 of Figure 1.

Figure 11 is a section of the case showing the top and the feed plate in bottom plan view.

Figure 12 is a top plan view of the closure for the case and the spring plate for supporting the cards in a position for discharge.

Figure 13 is a section on the line 13—13 of Figure 4.

Figure 14 is a section similar to that shown in Figure 13, but showing a card partly ejected for removal from the case.

Figure 15 is a section on the line 15—15 of Figure 4.

Figure 16 is a top plan view of the spring plate used in connection with the form shown in Figure 4 for supporting the cards.

Figure 17 is a bottom plan view of the top, with parts of the walls thereof broken away.

Figure 18 is an edge elevation of the bottom used in connection with the top shown in Figure 17.

Figure 19 is a top plan view of the bottom.

Figure 20 is a section on the line 20—20 of Figure 4.

Figure 21 is a section on the line 21—21 of Figure 20.

Figure 22 is a section on the line 22—22 of Figure 20.

Figure 23 is an end elevation of the bottom shown in Figures 18 and 19.

The card holder shown in Figure 1 consists of a rectangular case having a bottom 1, lateral edge walls 2, a top 3 and an end wall 4, which has therein adjacent the top a slot 5, through which cards may be discharged one at a time. The other end 6 of the case is open and is adapted to receive a card-supporting means, with means thereon for pressing the cards against the top of the case.

The top has therein a longitudinally disposed slot 7, which may have around it a bead 8. This bead is found in the form shown in Figure 4 but may be used with any of the forms. Around the case, extending from one edge of the slot to the other edge of the slot, is a leather casing 9, suitably attached to the case and forming an outer covering for the container. On the bottom of the case is a slide plate 10, which has at one end a closure 11, adapted to fit within the end of the case and contact the open end of the case by means of a flange 11a, which extends entirely around all sides and the ends of this closure.

This flange may be gripped for removing the slide plate from the case when it is desired to resupply the case with cards. This plate when positioned within the case does not extend the full length of the case, from the open end thereof to the closed end, and has on its end remote from

the closure, a spring plate 12 which is concavo-convex and attached to the slide plate at the center of its convex side, which is clearly shown in Figures 8 and 9. This spring plate may be attached to the slide plate in any suitable manner. In the present instance these plates are welded together.

On each end of the closure is a projection 13 forming a spacer, serving to prevent the ends of the cards from contacting the closure so there is always a small space between the ends of the cards and the closure in order that a flange on one end of a feed plate 14 may fit in between the end of one card and the closure for feeding this card out through the slot 5.

The feed plate lies immediately below the top of the case and has a hole 15 therein, which has therein one end of a pin 16 which passes through the slot 7 and is provided with a head 17 for holding the plate in position immediately below the top, and for moving the plate longitudinally for discharging a card. At one end of this feed plate and at each side thereof is a notch 18, and between these notches there is formed on the end 25 of the plate, adjacent the closure, a flange 19 for engaging the end of the card to discharge it through the slot.

The form of card holder shown in Figure 1 is adapted to be used for business cards, while the form shown in Figure 4 is adapted to be used by women for visiting cards. The holder shown in Figure 4 is composed of two members, one a top member 20 and the other a bottom member 21, which has its bottom side polished, as indicated by the numeral 22, to form a mirror.

Each form of case is adapted to contain cards 23, but of different sizes. The top member 20 has therein a slot 24, surrounded by a bead 8. This top member has an end wall 25 and lateral edge walls 26. These walls have inwardly projecting flanges 27 around their lower edges. The end of the top remote from the wall is open, as indicated by the numeral 28.

The top adjacent the open end thereof is made thicker to provide a slight projection 29, while at the closed end of the top there are two spacer plates 30 which extend partly along the main body of the top, as indicated by the numeral 31, and at right angles to the spacer parts of the plates. Supported in the top is a feed plate 32, which has at one end a downwardly extending flange 32a adapted to fit in between the spacer plates 30, and between the end of the top and one end of one of the cards for discharging the card. The feed plate at each end of the flange 32a has a notch 33 therein to receive the parts 31 of the spacer plates.

The feed plate has a hole 34 therein, in which one end of a pin 35 is fastened. This pin extends through the slot 24 and has on its outer end a head 36 for supporting the plate on the top, and for moving the plate for discharging the cards. Cooperating with this top member is the bottom member 21, which has lateral edge walls 38, each of which has at one end a notch 39.

At the other end of the bottom from the notches 39 the bottom has an end wall 40, which is not as high as the lateral edge walls and provides, in cooperation with the top, a space 41 through which the cards are discharged. This bottom is provided with a bead 42, immediately below the end wall 40 for the purpose of gripping the bottom to remove it from the top. Loosely supported on the bottom is a concavo-convex spring plate 43, which has its ends ex-

tending upwardly for supporting cards and urging the cards upwardly against the top so the cards may be discharged one at a time through the space 41.

To form the complete holder the bottom is inserted in the top and is held therein by means of the flanges 27. When the bottom is positioned within the top and a supply of cards is located therein, the cards may be discharged one at a time by moving the feed plate longitudinally by 10 means of the head 36. When it is desired to discharge a card the feed plate is pushed back so that the flange on the end thereof drops down between the end of a card and the end of the top. When the parts are in this position a forward 15 movement of the head 36 will cause a card to be partly ejected from the case so it may be easily gripped between the fingers and the thumb and removed.

In order to remove another card the feed plate 20 is moved back so that the flange will again drop behind another card and between the end of this card and the end of the top. These operations are repeated until the entire supply of cards in the case is removed. In order to place other 25 cards in the case the bottom is slid out of the top, other cards are placed on the spring therein and the bottom is again inserted in the top, after which the discharging operations may be performed for delivering other cards.

The cases are made of some suitable material. It is preferable that the case shown in Figure 4 have its bottom made of such material as will take a high polish so its surface may serve as a mirror. These cases are of sufficient size that 35 they may be easily carried in pockets or hand-bags.

It will be understood that I desire to comprehend within my invention such modifications as come within the scope of my claims and my 40 invention.

Having thus fully described my invention, what I claim as new and desire to secure by Letters Patent, is:

1. In a card holder, a case open at one end and having a slot in the other end adjacent one side, a flanged plate slidable within the case, the upstanding flange portion of which comprises a closure for the open end the base portion of which is of less length than the case, and a concave 45 spring plate medially attached adjacent the end of said relatively short base portion of the flanged plate to support cards and urge them toward said one side of the case, and means supported by said one side to deliver the cards one at a time through 55 the slot.

2. In a card holder, a case open at one end and having a slot in the other end adjacent one side, an L-shaped plate slidable within the case, the upstanding portion of which forms a closure for 60 said open end and a concave spring plate having its convex side medially attached to the base portion of said flanged plate to support cards and urge them toward said one side of the case, and a reciprocatory plate having a flange on one end 65 to engage the cards one at a time to deliver them through the slot.

3. In a card holder, a case open at one end and having a slot in the other end adjacent one side, an L-shaped closure for said open end including 70 a slide plate adapted to extend into the case, an arcuate spring plate having its convex side medially attached to the slide plate to support cards and urge them toward said one side of the case, and a plate slidably supported by said one side 75

adapted to engage the cards one at a time to deliver them through the slot.

4. In a card holder, a case having a slot at one end adjacent one side, resilient means within the case to support cards and urge them toward said one side of the case, L-shaped spacers at adjacent corners of the case and conforming to the angle of one side and one end thereof serving to hold the ends of the cards spaced from said side and end of the case, and means adapted to fit between the spacers to engage the ends of the cards to deliver them through the slot one at a time.

5. In a card holder, a case having a slot in one end adjacent one side, spacers within the case intermediate the card supply and the aforementioned side thereof and the end thereof opposite that having said slot, resilient means within the case to support cards and urge them toward said one side of the case, the spacers serving to hold the ends of the cards spaced from the said side end of the case and a feed plate between the cards and said one side, said feed plate having at one end on each edge a notch affording clearance for the spacers and a flange between the notches to extend between the spacers to engage the ends of the cards to deliver them one at a time through the slot.

6. In a card holder, a case open at one end and having a slot in the other end adjacent one side, a closure for said open end, spacers extending from one side to the other of the case at the end opposite that having said slot, resilient means within the case to support cards and urge them toward said one side of the case, the spacers serving to hold the ends of all the cards spaced from the end of the case, a feed plate between the cards and said one side, said feed plate having at one end on each edge a notch and a flange between the notches to extend between the spacers to engage the ends of the cards to deliver them one at a time through the slot, and means to support the feed plate on the case and move it to deliver the cards.

7. In a card case, a top having one end wall and lateral edge walls, stops on the overlying cover wall of said top and overhanging the card supply, a bottom having lateral edge walls and one end wall of less height than the edge walls, means to support the bottom in the top so that the end wall of the bottom forms with the top a slot for the discharge of cards, and means adapted to extend between the stops and engage a card at one end to discharge it through the slot.

8. In a card case, a top having one end wall and lateral edge walls, inverted L-shaped stops on the cover wall of said top and the end wall thereof, a bottom having lateral edge walls and one end wall of less height than the edge walls, means to support the bottom in the top so that the end wall of the bottom forms with the top a slot for the discharge of cards, a spring plate on the bottom to urge the cards upwardly against the overhanging portions of the stops and to support the cards so that they may be discharged one at a time through the slot, and means between the cards and the top adapted to extend between the stops and engage a card at one end to discharge it through the slot.

9. In a card case, a top having one end wall and lateral edge walls, stops in the top overhanging the card supply, a bottom having lateral edge walls and one end wall of less height than the edge walls, means to support the bottom in the

top so that the end wall of the bottom forms with the top a slot for the discharge of cards, a spring plate on the bottom to support the cards so that they may be discharged one at a time through the slot, and a reciprocatory ejector plate having notches to receive the stops and a flange to engage the cards mounted for reciprocation between the cards and the top adapted to extend between the stops and engage a card at one end to discharge it through the slot.

10. A card case including two telescopically adjustable complementary sections, one of the sections including a top panel, side walls and one end wall, said section being open at its opposite end, the second section including a bottom panel slidable within the first section and an end wall carried thereby forming a closure for the open end of the first section, an arcuate spring plate for the convex side of which said slidable bottom of the second section forms an abutment and the ends of which are engageable against a pack of cards enclosed within the adjusted sections to press the card pack toward the top panel of the first section, a reciprocatory ejector slide mounted on the inner side of the said top panel, said ejector slide having reentrant notches in its rear corners inwardly projecting spaced portions upon the end wall of one of the sections extending within said notches when the ejector slide is retracted, said projections serving to limit the retractive movement of the cards to less than the maximum range of retractive movement of the ejector slide, and an operating button on the slide extending through a slot in the top panel for actuating the slide to eject cards one at a time through a slot in the forward end of said case.

11. In a card holder, a case portion having one end and side walls and open at its opposite end, a second case portion slidable within the first portion likewise open at one end and including an upstanding end wall at its opposite end forming a closure for the open end of the first section when said portions are in adjusted relation, a concave spring plate enclosed between said portions with its medial concave side abutting upon one of the portions and its ends engageable with enclosed cards to press said cards toward the opposite side of the case, and a reciprocatory plate having a flange thereon to engage the cards one at a time for delivery from the case.

12. In a card case, two telescopically adjustable sections, each including a side panel and one end wall, both sections being open at their opposite ends, longitudinal edge walls on at least one of the sections, an arcuate spring plate confined between the sections with its convex side abutting upon the side panel of one of the sections and its ends engageable with a pack of cards for urging the cards toward the side panel of the other section, an ejector plate slidably mounted on the last mentioned side panel, said ejector slide having notches in its rear corners, and spaced stops on the end wall of one of the sections projecting within the corner notches of the ejector slide when the latter is retracted, said stops limiting the retractive motion of the cards to less than that of the slide, and a flange upon the margin of the slide intermediate the notches engageable with the cards one by one to eject the cards singly from the case through a discharge opening in the opposite end of the case, and means for reciprocating the slide.

CERTIFICATE OF CORRECTION.
